METAL TUBE BENDING MACHINE

Frederick L. Duer, Chicago, Ill.

Application June 23, 1941, Serial No. 399,301

3 Claims. (Cl. 153—40)

This invention relates to improvements in metal tube bending machines of the rotatable bending form character, having for an object to provide a machine so constructed and operable as to permit of material quickening of the work of tube bending and afford considerably greater production, operating and maintenance economies.

It is also an object of the invention to provide a metal bending machine which, by reason of the novel arrangement and predetermined automatic adjustment or regulation of movement of rotatable bending forms, will operate to effect rapid yet extremely accurate bending of tubes or other materials to uniformly pattern duplicating angular degrees, hence insuring finished products possessed of overall corresponding formations.

Another object of the invention resides in providing the machine with adjustable mechanical means adjustable for automatically controlling or governing the extent of movement of the rotatable bending forms.

A still further object of the invention is to provide the machine with a durable and rugged work clamping device cooperable with the particularly used rotatable bending form for permitting the materials to be bent to be quickly yet securely clamped or locked in proper and accurate relationship to such bending form and as quickly moved to inoperative or released position to expedite rapid removal of the bent materials from engagement with the bending form or adjustment of the materials to different positions for additional bending operations.

Other objects of the invention will be in part obvious and in part pointed out hereinafter.

In order that the invention and its mode of operation may be readily understood by those skilled in the art to which it appertains, I have in the accompanying drawings and the detailed description based thereupon, set out one embodiment of my invention.

In the drawings:

Figure 1 is a plan view of the improved machine with a part broken away.

Figure 2 is a side elevation of the same with a part of the illustrated supporting pillar broken away.

Figure 3 is an enlarged end elevation of the machine showing the mounting of the form receiving and supporting table, means for transmitting rotary motion thereto, and the tube holding clamp in operative position, the inopera-

tive position of such clamp being also shown in dotted lines.

Figure 4 is an enlarged fragmentary horizontal section taken on line 4—4 of Figure 2, looking in the direction in which the arrows point.

Figure 5 is an enlarged transverse section taken on the line 5—5 of Figure 2, looking in the direction in which the arrows point; and

Figure 6 is a perspective view of a particular form of chair frame, the structural tubing of which has been bent by the improved machine.

Having more particular reference to the drawings, in connection with which like characters of reference will designate corresponding parts throughout, the improved machine is provided with a supporting frame which consists of a metal base 1 and an upright or supporting pillar 2 fixed to a portion thereof.

A horizontally disposed bed 3 is fixedly mounted, adjacent one end, as at 4, to the upper end of the pillar 2, and receives and supports thereupon the working elements of the improved bending machine. The normally upper side of the bed 3 has transversely disposed and relatively spaced pairs of guide plates 5 adjustably secured thereto through the medium of screws or bolts 6, and slidably receive rails or bars 7 therebetween. The rails 7, because of slidable reception between the paired guide plates 5, obviously, are capable of transverse sliding adjustment with respect to the bed 3. Screw-threaded rods 8 are arranged transversely of the bed 3 and have their screw-threaded shank portions engaged through brackets 9 mounted on the outer side of said bed; adjusting nuts 10 being turned into engagement with the brackets outwardly thereof and adapted to have bearing upon the same, for a purpose which will be subsequently described. Carried upon the normally inner end portions of the rails 7 is a longitudinally disposed bar 11, fixedly connected to adjacent portions of the rails by means of screws or bolts 12. A sleeve or tube 13, provided adjacent its normally inner end with a laterally disposed finger 14, is arranged upon the normally rearward end portion of the bar 11, as shown in Figures 1 and 2, and is rigidly secured to said bar, as at 15. It fixedly carries a laterally disposed bracket arm 16 upon its rearward end portion. Upon the normally forward end portion of the rail carried bar 11, is a rotatably mounted and horizontally positioned roller 17, so located that it is substantially adjacent the forward end of the bed 3.

A secondary supporting bed or frame 18, pro-

vided with an extension or connection portion 19 is fixedly secured to the normally forward end of the bed 3. This secondary bed has a vertically disposed shaft 20 suitably journaled therein, preferably through the usage of anti-frictional bearings, generally designated by the numeral 21, and has a gear 22 splined thereto over a portion of the same through a locking nut 23; the gear 22, obviously being disposed in a horizontal plane. The upper end of the shaft 20 is extended above or beyond the upper side of the secondary frame 18 and is reduced, as at 24 and fixedly engaged through an appropriate opening formed in a horizontally positioned table 25, spaced from the adjacent upper side of said secondary frame and overlying a collar or plate 26. It will be thus understood that with rotation of the shaft 20 and its gear 22, corresponding rotary motion will be transmitted to the table 25. The lower end of the shaft 20 is locked against vertical displacement with respect to the frame 18 by engagement of a lock nut 20' on the screw-threaded lower end of the same and having bearing upon an adjacent portion of said frame.

Disposed longitudinally of the bar 11 is a mandrel 27, the normally rearward portion of which is arranged in proximity to the tube 13 and has its end adjustably connected through and to the bracket arm 16 by engaging an adjusting nut 28 therewith. The remaining or forward portion of the mandrel 27, as will be noted upon reference to the Figures 1 and 2, extends to a point in proximity to the frame 18, serving as a guide and retaining means for tubing 29 to be bent by the machine. An adjustable stop 30 is slidably mounted on the mandrel 27 and is adapted to be secured in an adjusted position thereon through the medium of a locking screw 31.

In order that the tubing 29 may be effectually bent to a predetermined angle or shape by usage of the improved machine, I provide a bending form assembly retaining or receiving plate 32 on which a semi-circular peripherally grooved bending form 33 is fixedly mounted, said plate 32 and bending form 33 being provided with aligned openings through which a portion of the reduced upper portion 24 of the shaft 20 is received. The plate 32 thus arranged upon the table 25 and receiving the reduced upper portion 24 of the shaft 20 therethrough, is fixedly secured to said table by engaging bolts or other suitable fastening devices therethrough and through adjacent portions of the table 25. In consequence, it will be understood that the bending assembly received upon the plate 32 is removable or interchangeable as and when desired.

Secured to the plate 32 adjacent the inner end of the grooved periphery of the bending form 33 and in consequence, adjacent to the corresponding portion of said bending form, is a fixed clamp jaw 34. It will be noted that the fixed clamp jaw is locked or otherwise secured to appropriate portions of the plate 32 by engaging bolts or similar fastening devices 35 therethrough and through adjacent portions of the plate. The locating of the fixed clamping jaw 34 with respect to the bending form 33 is such that its grooved work receiving and engaging face or side 34' aligns and is contiguous with the adjacent end of the peripheral groove of the bending form 33. Relatively spaced and slotted fingers 36 are fixedly carried upon the normally outer or rearward side of the fixed clamp jaw 34 and receive the opposite ends of a pivot pin 37 therein; the intermediate por-

tion of said pin being engaged through the adjacent lateral extremity or end of a substantially U-shaped work clamp body 38. An adjusting screw 39 is transversely engaged through a screw-threaded opening in an intermediate portion of the jaw 34 and is adapted to have adjusting engagement with the adjacent side of the pivotally connected extremity of said body 38 for a purpose which will be presently apparent. A movable clamp jaw 40 is provided the work clamp and as will be noted, has its inner or work engaging face grooved as at 40', to correspond to the grooved formation of the fixed clamp jaw 34. The jaw 40 is pivotally mounted between the extremities of a bifurcated operating lever 41, as at 42 and, as will be noted, said lever is of angular formation whereby the outer or free body portion thereof will extend upwardly and away from the plate 32 for operation convenience; a handle 42' being carried by the outer portion of the lever to facilitate its usage or operation. Connecting links 43 are pivotally connected adjacent certain of their ends to the bifurcated or opposite sides of the lever 41 adjacent the elbow of its angular formation, and the opposite or remaining ends of said links are pivotally connected to the remaining extremity of the substantially U-shaped body 38, as at 44. Pivotal movement of the operating lever 41 is adjustably limitable in one direction, 30 by means of an adjusting stop screw 45 mounted upon an extension 46 integral with the normally outer portion of the body 38, i. e., that portion to which the links 43 are pivotally connected. Pivotal movement of said operating lever in the opposite direction is limited by means of a lug 47 fixed or integral with an appropriate portion of the body 38, so that when the lever handle 42' is grasped and pulled in an upward direction, the adjacent bifurcated portion of said lever 41 will 40 be brought into engagement with said lug 47. Upon continued upward movement or pull of the lever 41 through its handle 42', it will be seen that the work clamp body 38 will be swung upwardly to a work disengaged or disengaging position, as shown in dotted lines in Figure 3 of the accompanying drawings. Assuming that the tubing 29 is properly arranged in the machine for bending, the work clamp body 38 is now swung downwardly to the position shown in full lines 50 in Figure 3 and a continuing downward thrust is imparted to the handle 42' of the movable jaw operating lever 41, resulting in the inward lateral movement of the movable clamp jaw 40 into positive clamping or gripping engagement with the adjacent surface of the tube 29 arranged or engaged in the grooved portion 34' of the fixed clamp jaw 34. In this way, it will be understood that the engaged or clamped portion of the tube 29 will be locked or fixedly positioned with respect to the bending form assembly and particularly, with relation to the bending form 33. The extent of clamping engagement between the work clamp jaws 34 and 40, obviously, may be either increased or decreased by inward or outward adjusting of the adjusting screw 39 in or 60 through the fixed work clamp jaw 34. If so desired, effectual relative alignment between the work clamp jaws 34 and 40 may be insured by providing the movable clamp jaw 40 with a laterally extending guide finger 48, adapted to have sliding overlapping engagement with the corresponding opposite side portion of the fixed clamp jaw 34, as is clearly shown in Figure 3 of the accompanying drawings.

With a view toward providing means for im-

parting rotation to the shaft 20 and hence, to the table 25 and the bending form assembly carried thereupon, I horizontally mount a jack cylinder 49 upon the normally rearward end of the machine bed 3, as shown in Figures 1 and 2 of the drawings. This cylinder is provided with the usual air or fluid inlet and outlet connections 50 and 51. It slidably receives therein a piston or plunger 52, the rod of which is passed from the cylinder through a suitable packing or stuffing gland 53 and has connection with a horizontally positioned rack bar 54 extending longitudinally of and along one side of the machine bed 3. The normally forward portion of said rack bar 54 has its teeth meshing with those of the gear 22. Such meshing engagement is maintained by application of inward pressure to the bar from a guide or retaining roller 55 supported in suitable journal brackets upon an adjacent side of the secondary supporting bed or frame 18, as at 56. Thus with outward movement of the piston or plunger 52 in its cylinder 49, corresponding motion of the rack bar 54 connected to said plunger will be transmitted to the gear 22 mounted on the vertically disposed shaft 20, hereinbefore described. Hence, this rectilinear motion of the rack bar 54 will be transmitted to the shaft 20 as rotary motion by reason of its being geared with the gear 22. By the same token, with movement of the piston or plunger 52 in its cylinder 49 in an opposite direction to that previously described, similar rotary motion will be imparted to the shaft 20, though in an opposite direction.

It is desirable that the extent of rectilinear movement of the rack bar 54, in one direction, under urge or influence of the plunger 52 shall be limited or predetermined, whereby different degrees or angles of bends may be effected in the tubing being worked upon in the machine; that is to say, the greater the extent of rotary movement of the shaft 20 and hence, the metal bending assembly, the greater the degree of bend imparted to the tubing being worked upon. To effect such predetermined limiting of movement of the rack bar 54, I rotatably mount a cylindrical body 57 upon a lower portion of the secondary bed or frame 18 in proximity to the normal path of travel of the rack bar 54. With the normally inwardly facing side or end of said body 57, I engage a plurality of relatively circularly disposed and outwardly extending screw-threaded stops or bolts, generally designated by the numeral 58. As shown in Figure 2 of the accompanying drawings, these adjustable stops are adapted to be turned so that their outer ends or heads are arranged at relatively different distances from the adjacent side or end of the body 57, thus, causing them to be arranged in relatively stepped relation to each other. Engageable with the rack bar 54 is a substantially U-shaped bracket 59, one side of which is provided with inwardly disposed teeth 59' adapted to be engaged with the teeth on the inner side of the rack bar 54 and to be adjustably or releasably retained in such engagement by means of locking screws 60. Accordingly, with inward turning of the screws 60, the U-shaped bracket 59 will be fixedly secured in a particularly adjusted position or relation upon the rack bar 54. This adjusted positioning of the bracket 59 upon the rack bar 54 is such that a portion thereof, with rectilinear movement of the rack bar 54 in one direction, will be brought into abutting engagement with the uppermost or preselected adjustable stop 58 carried by the rotatable body 57; the

latter having been previously rotated to a position whereby to select a particular adjustable stop 58 for engagement with the bracket 59. Upon such engagement of the bracket 59 with one of the adjustable stops 58, it will be understood that further movement of the rack bar 54 in an outward direction with respect to the cylinder 49 will be checked or stopped and in consequence, that the transmission of rotary motion to the bending assembly will likewise be stopped and therefore, that the degree or angle of bend effected by the machine through its bending form 33 will be controlled to the desired nicety. Obviously, by preselecting different stops 58, movement of the rack bar 54 may be so modulated or controlled as to effect bends of different degrees or angles in the tubing being worked upon or bent by the machine.

Valved control mechanism, generally indicated by the numeral 61, is preferably provided the cylinder 49 and such mechanism may be controlled by the machine operator through the medium of a control rod 62 connected to the valve mechanism and extending therefrom to a point upon the machine convenient to its operator.

In operation of my improved machine, a length of tubing such as indicated by the numeral 29 is engaged over the mandrel 27 until the outer end thereof is brought into abutting engagement with the previously adjusted stop 30. The mandrel engaged tubing is now contacted by the guide roller 17 and received in a portion of the grooved peripheral surface of the bending form 33. With attainment of the proper positioning of the tubing 29, the work clamp is now swung from its inoperative position as shown in dotted lines in Figure 3 of the accompanying drawings to its lower or operative position as shown in full lines in the same figure. Downward pressure is applied to the handle 42' of the operating lever 41, causing the movable clamp jaw 40 to be brought into gripping or clamping engagement with the adjacent side or surface of the tubing 29 extending from the adjacent portion of the bending form 33 through the fixed clamp jaw 34. At this point, it will be understood that that portion of tubing 29 outwardly of the bending form 33 will be clampingly connected to the bending form 33 and likewise, through the work clamp to the plate 32 fixedly connected to the rotatable table 25. The valved control mechanism of the cylinder 49 is now actuated so as to cause the plunger 52 working therein to be moved outwardly or toward the bed 3, imparting rectilinear motion to the rack bar 54, which, by reason of its being intergeared with the gear 22 will effect rotation of the shaft 20, the table 25 and the tube bending assembly comprised of the plate 32, the bending form 33 and the work clamp. Such rotation will effect bending of the clampingly connected portion of the tubing 29 over or about the grooved peripheral surface of the bending form 33. The degree or angle of bend made in the tubing 29, as hereinbefore described, will be controlled or regulated according to the particularly preselected adjustable stop 58 and the resultant control of travel or extent of travel of the rack bar 54 under urge of its particular operating means. With the bend made, the work clamp is released; the tubing 29 readjusted for further bending; the rack bar 54 returned to its initial or starting position together with the tube bending assembly, whereupon the work clamp is reengaged with the now properly adjusted or readjusted tubing

29, following which further bending operations, degree or angle controlled through the adjustable stops 58, are effected.

It will be understood that by repositioning of the bracket 59 upon the rack bar 54, and by proper preselection of the adjustable stops 58 carried upon the rotatable cylinder 57, different lengths of working strokes of the rack bar 54 may be effected and that through the latter, different degrees of bends in the tubing being worked upon by the machine may be effected, such as conditions or preference may dictate. Also, it will be understood that by reason of the laterally adjustable mounting of the longitudinally disposed bar 11 upon the machine bed 3, through the rails 7, a wide range of lateral adjustment of the mandrel 21 supported by said bar 11 will be permitted with relation to the particular metal bending assembly carried upon and fixedly connected to the rotatable table 25.

I claim:

1. A bending machine, including a bed, a horizontal supporting bar, a mandrel carried by and disposed longitudinally of the bar, means supporting said bar received upon and transversely adjustable of said bed, a vertically disposed shaft journaled in bearings supported by the bed having its upper end extended above said bed, a gear on the shaft, drive means supported on the bed in spaced relation to said shaft and gear, a rack bar fixedly connected to said drive means disposed longitudinally of the bed meshing with said gear, a plurality of movably supported independently adjustable stops on the bed selectively movable into positions in the path of travel of said 35

rack bar, a bracket adjustable along said rack bar engageable, at times, with a particularly selected adjustable stop, and bending means removably engaged with the extended end of said shaft and rotatable thereby.

2. In combination with the work bending form of a metal bending machine, a substantially inverted U-shaped clamp body pivotally mounted in proximity to one side of said form, a fixed clamp jaw in proximity to the pivotally mounted portion of said body, an operating lever having an angularly formed inner portion, means pivotally connected to the opposite side of said body and to said operating lever adjacent the elbow of its angular formation, a movable clamp jaw connected to said lever and arranged in opposed relationship to said fixed clamp jaw, and adjustable stop means on the free side of said body engageable with said lever for limiting pivotal movement thereof in one direction.

3. In combination with the work bending form of a metal bending machine, a clamp body pivotally mounted in proximity to and in cooperative relation with said form, an adjustable clamp jaw in proximity to the pivotally mounted portion of said body, an operating lever, means swingably connecting said lever to the opposite side of said body, a clamp jaw pivotally connected to said lever in opposed relation to said lever in opposed relation to the first mentioned clamp jaw and slideable with respect to said body, and adjustable means on said opposite side of the body engageable with said lever, at times, for limiting its pivotal movement in one direction.

FREDERICK L. DUER.
